APPLIANCE FOR STROPPING OR HONING
RAZOR BLADESWilliam Henry Carter, Perry Barr, Birmingham,
and Allan William Blackwell Patch, Erdington,
Birmingham, EnglandApplication October 27, 1948, Serial No. 56,874
In Great Britain August 12, 1948

15 Claims. (Cl. 51—159)

1

This invention relates to razor stropping or honing devices and it has for its object a device or apparatus by which a lateral motion is imparted to the blade in addition to a longitudinal motion; which successively presents to the stropping or honing surface the edges of double-edged blades; which holds the blade at the correct angle relative to the stropping or honing surface while executing said motions; which also sets the blade properly; which has provision for taking up wear so as to maintain the correct angle; which incorporates a locating device for holding the blade in such a manner that it can adjust itself without constraint to the stropping or honing surface; which incorporates a holding device arranged for convenient and quick operation; which has a relatively small number of parts for providing the desired actions; which has a simple to-and-fro motion of the hand moved actuating part; which is so constructed as to have a long effective life; which can be manufactured relatively cheaply; and which is not liable to get out of order.

Reference may be had to the accompanying drawings in which Figure 1 is a side elevation of an appliance in accordance with the invention.

Figure 2 is an elevation similar to Figure 1 showing the rocking parts in positions alternative to those indicated in Figure 1.

Figure 3 is a side elevation showing the longitudinal movable carriage included in Figure 1.

Figure 4 is a plan view of Figure 1 with the upper plate and the blade carrier removed.

Figure 5 is an end elevation at right angles to Figure 1.

Figure 6 is an elevation at right angle to Figure 3.

Figure 7 is a sectional elevation on line B—B of Figure 3.

Figure 8 is an end view of the blade carrier and Figure 9 is a plan view of Figure 8, both looking in the direction of arrow in Figure 1.

In a convenient embodiment of the invention, the housing structure conveniently has the form of a rectangular section box with open ends, the preferred construction including a base plate 1, a channel section member 2 attached thereto, and a top plate 3 detachably connected to the said member 2, the upper surface of which plate 3 either forms or is coated with the abrasive to constitute a honing or stropping surface or member. The upright limbs 4 of the channel section member 2 are slotted longitudinally to form lower guide rails 5 and upper guide rails 6 for a longitudinally movable carriage hereinafter described

2

as the primary carriage. The upper horizontal limb 7 of member 2 is shaped to incorporate a cam member 8, see Figure 4, and the hollow structure accommodates within its interior the mechanisms for moving the primary carriage and a secondary or lateral carriage mounted thereon.

The primary carriage takes the form of a trolley 9, Figures 3 and 4, supported on two lower transverse axles 10, 11, each of which has a grooved roller 12 at each end, with the side portions of the trolley frame connected by a transverse limb 13. A convenient way of building the primary and secondary carriages is by assembling together two channel section pieces one of which, i. e. of the primary carriage, carries the axles 10, 11 as described while the transverse limb of the other piece, i. e., of the secondary carriage 14 has its parallel limbs 15 up-turned to form anchorages for the pivots 16 of the articulated blade holder support 17.

To avoid up-and-down play between the carriage 9 and its guides, there are incorporated two other or upper transverse axles 18, 19 having their rollers 20 arranged to bear on the upper rails 6 of the guide in opposition to the first named rollers 12 which travel along the lower roller rails 5, the several rollers being sprung against their respective rails. A convenient way of carrying the upper axles 18, 19 is by a pair of axle supports of channel shape one at each end of the carriage in the form of a lever 21 articulated at one end to the lower axle 10 or 11 and carrying at its other end the upper axle 18 or 19. From the transverse limb of the lever depends an abutment lug 22 to a position below the lower axles 10—11, and between the two depending lugs is introduced a coiled compression spring 23 encircling a longitudinal rod 24. The reactive pressure of the compression spring urges apart the two lugs and thus transmits an upwardly-acting pressure to the upper axles 18—19 to resiliently bias or hold their rollers 20 against the upper guide rails 6, and by reaction an equal pressure but in a downward direction to the lower axles 10—11 to similarly hold their rollers 12 against the lower guide rails 5.

To enhance stability of the carriage, the wheel-base of the upper rollers exceeds that of the lower rollers. In this manner a very simple and stable carriage structure is obtained which provides the features of free longitudinal movement, and sustained inhibition of rattle.

The secondary or lateral carriage 14 which supports the articulated blade holder may consist of a transverse member or limb 14 up-turned at its two

ends 15 to receive the fulcra, slotted along its length for movement relative to a pair of upright guide rollers 25 fixedly journaled on limb 13, Figure 4, on the longitudinal carriage 9, and provided with an arm 26 extended forwardly to carry one of a plurality of rollers 27 which contact with and travel along the outside surface of the cam. Three rollers conveniently triangularly spaced are preferably adopted in the arrangement shown and spring pressed into contact with the opposite edges of the sinuous cam member 8 to avoid backlash and take up wear. The cam member 8 held static or stationary with the housing including base plate 1, member 2 and top plate 3 having the friction honing or stropping surface or member, has a number of hills and valleys or a pair of opposite series of cams in longitudinal alignment to give or impart a certain number of equal oscillations or to and fro lateral motions to the blade holder and blade hereinafter described, for each longitudinal stroke of the primary or main carriage 9. The two series of cams are spaced so that one series is the complement of the other, and the cam surfaces of one series are parallel to those of the other to form a two-sided track for the rollers 27 of the secondary carriage 14. Thus, a plurality of oscillations are imparted to the secondary carriage 14, blade holder and blade along a rectilinear path of the flat stropping or honing surface, during the movement of the primary carriage 9 in either direction to effectively treat the edge or edges of the blade. With the object of a simple construction, two of the rollers are journally mounted at the two ends of a lever 28 of the first order fulcrumed at its middle 29 on the transverse limb of the lateral or secondary carriage 14, a coiled tension spring 30 Figure 4 being hooked at one end to the forward arm 26 of the carriage and at the other to one end of the lever 28.

The cam 8 is of any suitable configuration but preferably has such a form as to produce a lateral displacement of the blade holder of about one-half of the normal safety blade width, four times for each longitudinal stroke of the actuating handle. As adumbrated hereinbefore, the cam is preferably of sinuous or zig-zag configuration, the latter consisting of four portions, two inclined in one direction and two inclined in the other direction; such portions are parallel-sided, joined to their neighbours by curved segments to provide easy transition and reversal of lateral direction, and make an angle of about 40° with the longitudinal carriage path. Alternatively, the cam contours may be continuous or sinuous curves.

The blade holder support 17, Figures 1, 8 and 9, is conveniently of channel configuration arranged with its transverse limb 31 about the stropping or honing surface and its two parallel limbs 32 extending downwardly to turn about the axes of fulcra 16 on the lateral carriage 14 when the blade is rocked at the ends of its longitudinal stroke through the agency of the actuating handle 33. Upon the upper surface of the transverse limb 31 is supported the blade holder proper to be described in detail later.

Means for rocking the blade holder support preferably include two levers 34, Figures 1, 2 and 5, of the first order fulcrumed at 35 on the sides of the longitudinal carriage 9 and extended upwardly to accommodate the transverse operating handle or piece 33 disposed at a higher level than the blade holder. These two levers 75

34 limit the rocking movement of the blade holder 17 and consequently the pressure applied to the blade edges, by stops 36, 37 at the ends of the levers arranged to abut from below respectively against the forward and rear upper axles 18, 19 of the longitudinal carriage 9, the rocking motion of the levers being transmitted to the blade holder support by a pin 38 extending laterally from the levers and of such length as to maintain engagement with slots 39 in the lower ends of the depending limbs 32 at the ends of transverse limb 31 of the blade holder support 17 for the full extent of the lateral movement. In this manner, reversal of the direction of the manual pressure applied to the rectilinearly-moving handle produces firstly a rocking of the blade 40 to a position where the edge is presented at the correct and precise angle to the stropping or honing surface of top plate 3, and successively the stropping or honing motion thereof.

Any appropriate means may be incorporated for securing the blade in position on its support. One such means illustrated in Figures 8 and 9 consists of a resilient arm 41 hinged at one end 42 to the transverse limb 31 of the support 17, and a self-acting detent 43 engaging a latching recess in the opposite limb 32 for retaining the arm in working position. For a two-edged blade, two upstanding pins 44 in the transverse limb 31 engage two outer holes in the arm 41 and blade 40, and the middle hole in the blade is located by a spheroidal projection 45 on the underside of the resilient arm 41 so that the blade has a restricted amount of freedom to seat and set itself on the stropping or honing surface.

Having thus described our invention, what we claim is:

1. Appliance for sharpening razor blades including a frame having at its upper part two laterally-spaced upright limbs and an upper part, an abrasive surface on the upper part, two longitudinal guide rails one above the other on each of said limbs, a roller-mounted carriage supporting a blade carrier and traversible along said rails, a pair of longitudinally-spaced rollers for each guide, and spring means for pressing the several rollers against their respective guide rails.

2. Appliance according to claim 1 in which the upper rollers are mounted on levers of the first order fulcrumed on the carriage, the limbs of the levers remote from the rollers being pressed apart by resilient means.

3. Appliance according to claim 1 having a second carriage movable laterally on the longitudinally-movable carriage, a static cam of sinuous configuration, and three rollers on the second carriage two of which are in contact with one edge of the cam and one in contact with the other edge of the cam, said rollers being resiliently pressed into contact with the cam edges.

4. Appliance for sharpening razor blades including a support having a static abrasive surface, a member slidably longitudinally on said support, a second member movable laterally on the first member, a blade carrier rockably carried by said second member, an operating handle for reciprocating the first member, fixed means on said support for imparting a plurality of lateral oscillatory movements in opposite divergent directions to the second member by reciprocation of the first member during movement thereof in each direction and means connecting

said handle with the blade carrier to rock the latter in alternate directions at the end of successive strokes of the handle, said means including a pair of levers of equal length fulcrumed on the first member to carry the operating handle, and stops on such member positioned to limit the rocking movement of the levers, and then to transmit reciprocating movement of the handle to the first member.

5. Appliance for sharpening razor blades including a channel-section housing structure incorporating upright side limbs slotted longitudinally to form guide rails and an upper transverse part having an abrasive surface, a member reciprocable on said rails, a second member movable laterally on the first member and provided with a blade carrier, and means for effecting such lateral movement of the second member during longitudinal displacement of the first member relative to the abrasive surface.

6. Appliance according to claim 5 in which the means for effecting the lateral movement are enclosed within the housing structure.

7. Appliance for sharpening double-edge razor blades including a frame having a stationary abrasive surface, a member slidable rectilinearly longitudinally on said frame in opposite directions with a plurality of interposed anti-friction means, means resiliently biasing said anti-friction means apart and into engagement with said frame, a transverse pivot carried by said member, a second member mounted on said pivot to be swingable longitudinally of said frame and in part movable laterally on the first member, and provided with a blade carrier, means coacting between the frame and second member for imparting a sinuous motion to the laterally movable part and blade carrier in a plurality of opposite oblique strokes during each longitudinal sliding motion of the first member in either direction, and means operatively connected to the first member whereby it may be slid in either direction, and operative to swing the second member and blade carrier together with a blade thereon in opposite directions to present the opposite edges of the blade toward and against the abrasive surface upon reversal of the direction of motion of the first member.

8. Appliance for sharpening double-edge razor blades including a frame having a stationary abrasive surface, a member slidable longitudinally of the frame and surface rectilinearly in opposite directions with a plurality of interposed anti-friction means, means resiliently biasing said anti-friction means apart and into engagement with said frame, a transverse pivot carried by said member, a second member swingable longitudinally and in part movable laterally on the first member, and provided with a blade carrier, means coacting between the frame and second member for imparting a sinuous motion to the laterally movable part and blade carrier in a plurality of criss-cross divergent angular motions simultaneously with the longitudinal motion in both directions, and means having limited movements on the slidable member for actuating the latter and acting by pressure to swing the blade carrier and blade to opposite inclined positions at predetermined pressure away from the direction of sliding motion upon reversal of the latter.

9. Appliance for sharpening double-edge razor blades including a frame having a stationary abrasive surface, a member slidable longitudinally on said frame in opposite directions with a plurality of interposed opposed anti-friction

means, means resiliently biasing said anti-friction means apart and into engagement with said frame, a transverse pivot carried by said member, a second member mounted on said pivot to be swingable longitudinally of said frame and in part movable laterally on the first member, and provided with a blade carrier, means coacting between the frame and second member for imparting a sinuous motion to the laterally movable part

10. Appliance for sharpening razor blades including a channel-section housing structure incorporating upright side limbs slotted longitudinally to form guide rails and an upper transverse part having an abrasive surface, a member reciprocable on said rails, a second member movable laterally on the first member and provided with a blade carrier, and means for effecting such lateral movement of the second member during longitudinal displacement of the first member relative to the abrasive surface.

15. Appliance according to claim 10 in which the upper contacts are mounted on levers of the first order fulcrumed on the carriage, the limbs of the levers remote from the contacts being pressed apart by resilient means.

20. Appliance for sharpening razor blades including a frame having an upper part with two laterally-spaced upright limbs and an abrasive surface on the upper part, two longitudinal guide rails one above the other on each of said limbs, a carriage supporting a blade carrier and traversable along said rails by longitudinal movement, a pair of longitudinally-spaced contacts for each guide rail, and spring means for pressing the several contacts against their respective guide rails some in opposition to others.

25. Appliance according to claim 20 in which the upper contacts are mounted on levers of the first order fulcrumed on the carriage, the limbs of the levers remote from the contacts being pressed apart by resilient means.

30. Appliance according to claim 25 in which the upper contacts are mounted on levers of the first order fulcrumed on the carriage, the limbs of the levers remote from the contacts being pressed apart by resilient means.

35. Appliance according to claim 25 in which the upper contacts are mounted on levers of the first order fulcrumed on the carriage, the limbs of the levers remote from the contacts being pressed apart by resilient means.

40. Appliance according to claim 35 in which the upper contacts are mounted on levers of the first order fulcrumed on the carriage, the limbs of the levers remote from the contacts being pressed apart by resilient means.

45. Appliance according to claim 35 in which the upper contacts are mounted on levers of the first order fulcrumed on the carriage, the limbs of the levers remote from the contacts being pressed apart by resilient means.

50. Appliance for sharpening razor blades including a support having an abrasive surface, a member slidable longitudinally thereof, a second member movable laterally on the first member and provided with a blade carrier, an operating handle for reciprocating the first member, a pair of levers fulcrumed on the first member, and on which the handle is mounted, a pair of levers fulcrumed on the second member and on which the blade carrier is mounted, means for imparting lateral movement to the second member by reciprocation of the first member, and means connecting said handle with the blade carrier to rock the latter in alternate directions at the end of successive strokes of the handle, rocking movement of the handle levers being communicated to the blade carrier levers by means which allow lateral movement of the second member relative to the first member.

55. Appliance for sharpening razor blades including a frame, a member fixed on said frame and having an abrasive surface thereon, a carriage slidable in a rectilinear path on the frame longitudinally of said surface, a second carriage laterally slidable on the first carriage and provided with a blade carrier, and a static cam of sinuous configuration fixed longitudinally of the frame and provided with a plural series of continuous oppositely acting cam portions arranged

to move the second carriage and blade carrier laterally a plurality of times in each of opposite divergent diagonal directions during each of its opposite longitudinal displacements in a rectilinear path, said second carriage having continuous contact with the cam at three triangularly-spaced positions at least one of which opposes the others located at like points on the cam.

15. Appliance for sharpening razor blades including a support having a static abrasive surface, a member slideable longitudinally on said support, a second member movable laterally on the first member, a blade carrier rockably carried by said second member, an operating handle for reciprocating the first member, fixed means on said support for imparting a plurality of lateral oscillatory movements in opposite divergent directions to the second member by reciprocation of the first member during movement thereof in each direction, and means connecting said handle 20 with the blade carrier to rock the latter in alternate directions at the end of successive strokes of the handle.

WILLIAM HENRY CARTER.
